UNITED STATES PATENT OFFICE.

DANIEL KOPS, OF NEW YORK, N. Y.

CORSET.

SPECIFICATION forming part of Letters Patent No. 631,079, dated August 15, 1899.

Application filed May 29, 1899. Serial No. 718,656. (No model.)

To all whom it may concern:

Be it known that I, DANIEL KOPS, a citizen of the United States, residing at New York city, in the county and State of New York, have invented an Improvement in Corsets, of which the following is a specification.

In the present style of corsets the sides are cut high on the hips. This style of corset is disadvantageous with both slight and stout figured persons. With slight persons the figure cannot be amplified, and with stout persons the lower edge of the corset is liable to press into the flesh over the hips, especially when in a sitting position; and the object of my invention is to overcome these difficulties and to improve the figure of the wearer.

My invention consists of a corset having a flexible extensible hip-section and a flexible under-arm section, connected together at about or slightly below the waist-line and at this point strengthened by a stiffening-strip placed approximately horizontal and against which the hip-section bears. The under-arm section is maintained flexible, and the hip-section is made with parallel vertical central stays, between which stays there is a bellows plait, preferably taper-ended. I also employ diagonal side stays and prefer to place one at each side of the two parallel central stays. The diagonal stays are farthest apart at their upper ends, and their lower ends come close to the lower ends of the parallel central stays, and said diagonal stays are inclined in the opposite direction to the taper of the flexible hip-section. In my improved corset the bone-pockets which are sewed to the fabric body at the front and back of the corset, and especially at the front, are set more slanting or diagonal than usual, so as to provide for the said flexible sections at the sides. The lower edge of the under-arm section at the stiffening-strip is folded outward, and the flexible hip-section is connected thereto and extends directly away from said section, so that there is no fold at the upper edge of the hip-section, and the parallel vertical stays and diagonal side stays at their upper ends stop against the stiffening-strip, so that in use the movement of the hip-section is stopped at about the waist and a riding-up of the corsets under

the arms is prevented. The stiffening-strip may be made with pockets and bones. The hip-section will conform to a slight figure, and the bellows plait permits the same to be extended or expanded to conform to the stout figure. I prefer to make the under surface of the hip-section with end pockets, so as to hold a pair of removable stay-bones which extend lengthwise across the hip-section over the hips and which may be used for the purpose of bowing the hip-section when the corset is worn by a person of slight figure.

In the drawings, Figure 1 is an elevation showing the side of a corset containing my improvement. Fig. 2 is an elevation of the inner surface of the same at the lower end. Fig. 3 is a vertical section at $x x$, and Fig. 4 is a horizontal section at $y y$, the said sections being of exaggerated size.

It will be noticed from the drawings that the bone-pocket strips $a b c$ are placed at a considerable inclination, extending from their upper ends back of the breast portion to their lower ends closely adjacent to the front steel, and that the back-bone pockets d are placed very near the back bones and eyelets of the corset. This construction leaves space for and makes it possible to use a flexible hip-section e and a flexible under-arm section f , the two sections being connected at about or slightly below the waist-line. The section Fig. 3 shows the preferable manner of connecting these two parts, wherein the lower edge of the under-arm section f is folded outwardly and the upper edge of the flexible hip-section e lies thereon and is joined at the sewing-line 2 and extends directly away from the lower edge of the section f . At this place I employ a stiffening-strip of fabric h , that extends approximately horizontally across the corset between the bone-pockets c and d . i and i' represent the parallel vertical central stays extending over the flexible hip-section between the lower edge of the corset and the stiffening-strip h . Between these stays $i i'$ I employ a bellows plait, preferably tapered toward both ends, so that when distended the greatest degree of extension or expansion is at the center of the hip-section, and I prefer to employ with these parts the diagonal side

stays *ll'*, the lower ends of which at the lower edge of the corset come close to the lower ends of the central stays and the upper ends of which side stays come close to the ends of the 5 stiffening-strip *h*, the said upper ends being the widest apart, while the widest part of the hip-section is at the lower edge of the corset.

The under surface of the hip-section at the respective sides is preferably made with end 10 pockets *m m'* to receive and hold a pair of removable stay-bones *o*, and these stay-bones may be centrally guided by loops of fabric 3, sewed to the under side of the hip-section, and they extend lengthwise across the hip- 15 section. These removable stay-bones *o* are advantageous where the corset is used by a person of slight figure, as then they may be employed to expand or extend the flexible hip-section, so as to amplify the figure of the 20 wearer, while with a person of stout figure these stay-bones would not be used. With a person of slight figure the bellows plait *k* would probably not come into use; but if the 25 corset be worn by a person of stout figure the fleshy hip would fill and extend or expand the hip-section and pull out the bellows plait, and said plait would act with the flexible hip-section to impart more perfect form to the 30 figure of the wearer and to confine the flesh below the corset.

The stiffening-strip *h* is especially advantageous in connection with the bone-pockets *c* and *d* to form a stop for the action of the hip-section and the central and diagonal stays 35 in use, especially when the wearer of the corset sits down. This action is especially noticeable with a person of stout figure, where the hip-section would tend to rise slightly and extend outward more than the same would in 40 a standing position, and the rising action would cause the strain to be taken at about the waist upon the fabric of the corset and the stiffening-strip *h*. The movement and the strain being confined to these parts, the 45 flexible under-arm section would not be affected, and the corset would not have an unpleasant tendency to rise, as would be the case if there were no horizontal point to check the movement of the hip-stays. The stiffen- 50 ing-strip *h* performs another office in that it covers the point of union of the flexible under-arm section and the flexible hip-section and prevents rubbing and loosening the sewed seam and prevents the edges of the fold act- 55 ing injuriously to wear the outer garment.

I claim as my invention—

1. A corset comprising with the fabric body and bone-pockets a flexible hip-section, a stiffening-strip extending across at the upper 60 edge of the same at about or slightly below the waist-line, a central bellows plait extending from the stiffening-strip to the lower edge of the corset and stays adjacent to said plait upon the surface of the flexible hip-section 65 between the said stiffening-strip and the lower edge of the corset, substantially as set forth.

2. A corset comprising a fabric body and bone-pockets, a flexible hip-section extending from about or below the waist-line to the lower edge of the corset, a stiffening-strip along the 70 upper edge of the flexible hip-section and sewed thereto, two parallel vertical central stays upon the hip-section extending from the stiffening-strip to the lower edge of the corset and a bellows plait between the two central 75 stays to provide for the extension of the hip-section, substantially as set forth.

3. A corset comprising a fabric body and bone-pockets, a flexible hip-section extending from about or below the waist-line to the 80 lower edge of the corset, a stiffening-strip along the upper edge of the flexible hip-section and sewed thereto, two parallel vertical central stays upon the hip-section extending from the stiffening-strip to the lower edge of the 85 corset and a taper-ended bellows plait between the two central stays to provide for the extension of the hip-section and diagonal stays also upon the surface of the flexible hip-section between the stiffening-strip and the 90 lower edge of the corset, substantially as set forth.

4. A corset comprising a fabric body and bone-pockets, a flexible hip-section extending from the lower edge to about or below the 95 waist-line, a flexible under-arm section ex- 100 tends from about the waist-line to the upper edge of the corset, the lower edge of the under-arm section being folded and the upper edge of the hip-section not folded where the two are joined together by a line of sewing, a stiffening-strip extending across the union of the 105 hip and under-arm sections and covering and protecting the fold, substantially as set forth.

5. A corset comprising a fabric body and bone-pockets, a flexible hip-section extending from the lower edge to about the waist-line, a flexible under-arm section extending from about the waist-line to the upper edge 110 of the corset, the lower edge of the under-arm section being folded and the upper edge of the hip-section not folded where the two are joined together by a line of sewing, a stiffen- 115 ing-strip extending across the union of the hip and under-arm sections and covering and protecting the fold, two parallel vertical central stays upon the hip-section extending from the stiffening-strip to the lower edge of the 120 corset and a bellows plait between the two central stays to provide for the expansion of the hip-section, and diagonal stays laid upon the surface of the flexible hip-section between the stiffening-strip and the lower edge of the cor- 125 set, substantially as set forth.

6. A corset comprising a fabric body and bone-pockets, a flexible hip-section extending from about or below the waist-line to the lower edge of the corset, a stiffening-strip along the upper edge of the flexible hip-section and sewed thereto, two parallel vertical 130 central stays upon the hip-section extending

from the stiffening-strip to the lower edge of the corset, and a bellows plait between the two central stays to provide for the extension of the hip-section, the end pockets upon the 5 under surface of the hip-section and the removable stay-bones extending lengthwise across the under side of the hip-section with

the ends in said pockets, substantially as set forth.

Signed by me this 24th day of May, 1899.
DANIEL KOPS.
